FIG. 3.

FIG. 4.

INVENTOR
JOHN J. GILBERT
By *W. J. G.* ATTORNEY

UNITED STATES PATENT OFFICE

JOHN JOSEPH GILBERT, OF PORT WASHINGTON, NEW YORK, ASSIGNOR TO WESTERN ELECTRIC COMPANY, INCORPORATED, OF NEW YORK, N. Y., A CORPORATION OF NEW YORK

SUBMARINE CABLE INSULATION

Application filed April 29, 1926. Serial No. 105,390.

This invention relates to submarine cables for telephony and telegraphy and particularly to cables for deep sea service where the conductor is subjected to high pressure and 5 low temperature.

One of the most serious problems in signaling by submarine cable is the attenuation of the signals. While this is detrimental in low frequency telegraphy, the effect is much 10 greater in high frequency telegraphy and the still higher frequencies of telephony for which present day cables are designed. More especially is this so when cables are subjected to the extremely high pressure and 15 low temperature present at great depths.

An object of the present invention is to reduce the attenuation of signals transmitted over submarine cables.

A more specific object is the reduction of 20 the leakance losses in such cables.

One method of attaining these objects becomes evident from a study of the factors upon which the attenuation constant of the 25 cable depends. This constant a may be calculated from the formula

$$\frac{1}{2} \sqrt{\frac{C}{L}} \left(R + L \frac{G}{C} \right)$$

in which R is the effective resistance, L the 30 inductance, C the capacity and G the leakance per nautical mile of cable. The expression

$$\frac{G}{C}$$

is considered as a single quantity throughout 35 this specification because in the testing of dielectric materials it has become the general practice to consider this expression 40 rather than the leakance G alone. This is because the shape of the sample under test will affect both the capacity and the leakance but in such a way that the quantity

$$\frac{G}{C}$$

remains constant and varies only with the 45 dielectric material. Considerable mathematical calculation is thereby avoided.

It is obvious that for a cable having a given resistance, inductance and capacity, the attenuation constant will have the smallest value when an insulating material is employed which has a value of 55

$$\frac{G}{C}$$

as small as possible. It is also seen that the 60 effect of leakance upon the attenuation constant increases as the inductance of the cable increases and for this reason the effect of leakance on a loaded conductor is of the utmost importance. The leakance of a coil loaded cable is largely dependent upon the 65 leakance of the sections of non-loaded conductor between the loading coils and may therefore be reduced by the same means which will reduce the leakance of a non-loaded cable. 70

In the formula for the attenuation constant the quantity

$$\frac{G}{C}$$

is to be multiplied by the inductance L . It 75 might therefore appear that for a so-called non-loaded cable the leakance would have no effect. It must be remembered however, that even a non-loaded conductor has an appreciable inductance amounting to .001 80 henry or more per nautical mile due to the magnetic fields set up in the sea water surrounding the cable.

Submarine cables when laid in deep water 85 are ordinarily subjected to very great pressure due to the weight of the water above the cable, the depth at which the cable is laid determining the amount of this pressure. Trans-oceanic cables are subjected to pressures of over 2500 pounds per square inch 90 for the greater part of their length and a considerable portion of the cable is usually subjected to pressures ranging from 5000 to 10,000 pounds per square inch. 95

The temperature of the water at the ocean bottom is usually in the neighborhood of 4° C. and the temperature of the cable and insulation is therefore the same.

Although these extreme conditions of pres- 100

sure and temperature have been known to exist, but little attention has been given to the effect upon the insulation material other than to insure that the insulation was impervious to water under these conditions.

5 The insulation used at the present time for submarine cables is usually gutta percha applied in a layer about 120 mils or more thick, the thickness depending upon such factors as 10 the operating potential and the insurance of mechanical integrity.

15 In the manufacture of submarine cables it is usual to apply a "flux" material, such as Chatterton's compound to the conductor in order to insure adhesion between the conductor and insulation. This flux is applied in a very thin layer, about 1 mil in thickness, before the insulation is applied. In a 20 coperding application for A. R. Kemp, issued as Patent No. 1,700,766 on February 5, 1929 is described a continuously loaded conductor in which bitumen was applied in a thick layer filling the interstices between the loading material and the conductor so as to 25 act as a cushion substance to relieve strains set up in the loading material during the manufacture and the laying of the cable. It also served the additional purpose of a flux for the gutta percha insulation. Up to the 30 present time, however, there has been no use of bitumen as a flux between the conductor and the insulation of non-loaded or coil loaded cables.

35 The insulation materials applied to conductors heretofore have seldom been chosen with reference to their characteristics under the actual operating conditions of high pressure and low temperature. It has, however, been known for some time, among cable manufacturers, that the capacity and the leakance of insulation varies with changes in pressure and temperature and specifically that the leakance of gutta percha increases with an increase in pressure and with a decrease in 40 temperature.

45 It has also been known that the leakance is, to a limited extent, proportional to the frequency of the impulses transmitted over the cable. For this reason the leakance of a 50 cable for high frequency telegraph or telephone operation is considerably greater than that of the same cable for direct current telegraph operation. Furthermore the attenuation constant is mostly affected by the characteristics of the layers of insulation nearest the conductor, that is within a thickness of 55 from 20 to 30 mils from the surface of the conductor.

60 From experiments conducted in connection with the present invention it is now found that the quantity

$\frac{G}{C'}$

65 for various substances depends upon the fre-

quency, temperature and pressure at which it is measured.

In accordance with this invention a submarine cable is contemplated for the transmission of signals, the frequencies of which 70 are those met with in telephone work or high speed telegraphy, under conditions of high pressure and low temperature present at great depths. Such a cable has a material, combined with the usual insulation, which decreases the leakance of the cable, under conditions of high pressure. This material is applied to the conductor and acts as a binder between the conductor and main insulation. Certain of the bitumens, and especially 80 asphalt, have been found very satisfactory for this purpose. The invention further contemplates a cable having one insulation, usually gutta percha, at moderate depths and a combination of gutta percha and a material 85 such as asphalt for the extreme depths.

In the accompanying drawings Fig. 1 indicates the variation of

$\frac{G}{C}$

90

for several materials when the pressure is varied and the frequency of the measuring current is 100 cycles per second; Fig. 2 is a set of curves for the same materials 95 subjected to varying pressures when the frequency of the measuring current is 1000 cycles per second; Fig. 3 shows a cross section of a cable using asphalt as the flux or binder between the conductor and gutta percha; and Fig. 4 shows a cable with different sections constructed to meet the requirements 100 at the respective ocean depths at which they are placed.

In constructing submarine cables in accordance with the present invention, the signaling conductor 10 (Fig. 3) is covered with a layer of insulating flux material 11, which may be asphalt, having the desired characteristics with reference to pressure and temperature. A layer 12 of gutta percha or other insulation is then applied over the asphalt flux. For protection etc., a layer of jute 13 is usually applied, then a layer of armor 14 and finally a second layer of jute 115

120 The thickness of the layer of flux or binder is dependent upon the material employed but for asphalt this layer should be about 10 to 20 mils. thick. Since the greater part 125 of the leakance losses occurs within a thickness of about 30 mils. of insulation, it would seem that a thicker flux would be of advantage but an increase in the thickness of asphalt beyond about 20 mils presents considerable difficulty in the manufacture of the cable and is therefore not feasible.

130 It must be remembered that the capacity of an insulated conductor is largely determined by the dielectric constant of the ma-

material closest to the conductor and it is necessary to insure that the arrangement described for reducing the value of

$$\frac{G}{C}$$

does not increase the capacity of the conductor and hence increase the attenuation constant. Under sea bottom conditions the dielectric constant of asphalt is less than that of gutta percha so that a decrease in capacity of the cable accompanies the decrease in

$$\frac{G}{C}$$

obtained by employing a layer of asphalt between the conductor and the gutta percha.

In Figs. 1 and 2 curves A represent the variations in

$$\frac{G}{C}$$

due to varying pressures, at a temperature of 4° C. and at frequencies of 100 and 1000 cycles per second, respectively, for a cable having a heavy layer of asphalt flux surrounded by gutta percha as shown in Fig. 3. Curves B represent corresponding variations for a cable insulated with ordinary gutta percha, which is made to adhere to the conductor by a thin coating of Chatterton's compound. Curves C represent the variations for a cable insulated with gutta percha which has been thoroughly washed and deresinated to improve its dielectric properties, and made to adhere to the conductor by a thin coating of Chatterton's compound.

As shown by these curves the value of

$$\frac{G}{C}$$

for a cable with a heavy layer of asphalt decreases with increasing pressure, whereas the value of

$$\frac{G}{C}$$

for a cable with the gutta percha insulation close to the conductor in general increases with the pressure.

From the curves of Fig. 1 taken at a transmitting frequency of 100 cycles per second it is apparent that with respect to the value of

$$\frac{G}{C}$$

and its effect upon the attenuation constant the cable having a heavy asphalt layer has an advantage over the cable having the insulation of ordinary gutta percha close to the conductor when used on depths where the pressure is above 4500 pounds per square inch. At pressures around 10,000 pounds per square inch it has been found that the

cable with a layer of asphalt in this respect is equal to that having the insulation of improved gutta percha close to the conductor, the value of

$$\frac{G}{C}$$

70

then being 14 in both cases.

The advantage of the asphalt flux is more pronounced at higher frequencies. From the curves of Fig. 2 it is evident that the cable having a layer of asphalt is far superior at all pressures to that having the ordinary gutta percha insulation close to the conductor, and excels at pressures above 2500 pounds per square inch the cable having the improved gutta percha insulation close to the conductor.

The use of a heavy layer of flux, such as mentioned above, therefore, has the effect, not only of serving as an effective binder, but also of reducing the leakance of a cable at the higher pressures to which submarine cables generally are subjected.

From a consideration of Figs. 1 and 2, it will be seen that some advantages may be obtained in both low frequency and high frequency cables by employing an insulation having low leakance under high pressure for the deep sea portions of the cable and gutta percha or other insulation material having low leakance at low pressures for the terminal or shallow water portions of the cable. This could be accomplished by employing a very thin layer of flux consisting of asphalt or similar material, 1 mil or so in thickness for shallow water portions and a thicker layer of flux for the deep sea portions of the cable.

Although bitumens and particularly asphalt have been mentioned as suitable for this purpose, it is contemplated that any material which has low leakance at high pressures and low temperatures may be employed to advantage.

The manner in which the insulation is applied to the conductor and its chemical composition is of little importance provided it has the desirable properties described above and is not in any way injurious to the remainder of the cable.

Such an arrangement is shown in Fig. 4, in which the cable 20 is shown as having a section 21 placed at a comparatively great ocean depth and a section 22 at a smaller depth. The figure particularly shows detail cross sections 23 and 24 of the respective sections, the cross sections showing a cable core similar to that shown in Fig. 3 without the protecting layers of jute and armoring. In the cross section 23 corresponding to the greater depth the layer 31 of a low leakance insulating material, placed between the conductor 30 and the outer insulation 32, is comparatively heavy. In the cross section 24

corresponding to the smaller depths the layer 31 is comparatively thin and may merely serve as a binder. The selection of the insulating materials and the dimensions of the 5 insulating layers would of course depend upon the transmission frequency and the depth at which the cable is to be located.

It is to be understood that this invention is applicable to the sections of coil loaded 0 cables between the loading points and also to non-loaded cables.

What is claimed is:

1. A non-loaded submarine telephone or 15 telegraph cable comprising a conductor and an insulating material closely surrounding said conductor, said insulating material having a decreasing leakance with increasing pressure.

2. A non-loaded submarine telephone or 20 telegraph cable comprising a conductor and an insulating material closely surrounding said conductor, said insulating material having a decreasing leakance with decreasing temperature.

3. A non-loaded submarine telephone or 25 telegraph cable comprising a conductor and an insulating material closely surrounding said conductor, said insulating material having a decreasing leakance with increasing 30 pressure and decreasing temperature.

4. A non-loaded section of a submarine 35 telephone or telegraph cable comprising a conductor, insulation for said conductor, and a second insulating means between said conductor and insulation and engaging said conductor, said second insulating means having a lower leakance than improved gutta percha for frequencies of the order of 1000 40 cycles when subjected to high pressure and low temperature.

5. A non-loaded section of a submarine 45 telephone or telegraph cable for transmitting frequencies of the order of 1000 cycles per second, comprising a conductor, insulation for 50 said conductor, and an insulating flux between said insulation and conductor and engaging said conductor, said flux comprising a material having a leakance lower than that of improved gutta percha at pressures in excess of 2500 pounds per square inch, and at 55 temperatures in the neighborhood of 4 degrees centigrade.

6. A non-loaded submarine telephone or 60 telegraph cable comprising a conductor, insulation for said conductor, and a layer of bitumen between said conductor and insulation and engaging said conductor.

7. In a non-loaded submarine telephone or 65 telegraph cable a conductor, insulation for said conductor comprising gutta percha, and means for reducing the leakance of said cable comprising a layer of bitumen between said conductor and said gutta percha insulation.

8. A submarine telephone and telegraph 70 cable comprising a conductor and composite

insulation therefor of bitumen and other insulating material, the amount of bitumen applied per unit length of the conductor being smaller on portions of the cable near the terminals than on portions more remote from the terminals to compensate for the effect of the difference in water pressures acting on 75 said portions.

9. A submarine telephone or telegraph 75 cable comprising a conductor, a main body of insulating material for said conductor and a layer of an insulating material different from that in said main body between said conductor and insulation, the thickness of 80 said layer being greater for certain portions of the cable than for other portions of the cable to compensate for the effect of the difference in water pressures acting on said portions.

10. In a submarine telephone or telegraph 85 cable, a conductor, an insulation therefor, said insulation comprising an insulating material having a decreasing leakance characteristic with respect to pressure and another 90 insulating material having an increasing leakance characteristic with respect to pressure, the weight ratio between said materials being different at different portions of said cable.

11. In a submarine telephone or telegraph 95 cable, a conductor, an insulation therefor, said insulation comprising an insulating material having an increasing leakance characteristic with respect to temperature and another insulating material having a decreasing 100 leakance characteristic with respect to temperature, the weight ratio between said materials being different at different portions of said cable.

12. In a submarine telephone or telegraph 105 cable, a conductor and insulation therefor, said insulation comprising an insulating material having a decreasing leakance characteristic with respect to pressure and an increasing leakance characteristic with respect 110 to temperature, and a second insulating material having an increasing leakance characteristic with respect to pressure and a decreasing leakance characteristic with respect to temperature, the weight ratio between said 115 materials being different at different portions of said cable.

13. A submarine cable for signaling frequencies of 1,000 cycles per second having a non-loaded deep sea section and a non-loaded 120 section for comparatively shallow depths of the sea, said cable comprising a conductor and an insulating envelope of gutta-percha therefor, and said deep sea section including a layer of bitumen contiguous to said conductor.

In witness whereof, I hereunto subscribe my name this 27th day of April, A. D., 1926.

JOHN J. GILBERT.
